UNITED STATES PATENT OFFICE.

HARRY E. CAMPBELL, OF BALTIMORE, MARYLAND, ASSIGNOR TO CAMPBELL METAL WINDOW CORPORATION, OF BALTIMORE, MARYLAND, A CORPORATION OF MARYLAND.

WINDOW.

Application filed July 14, 1923. Serial No. 651,506.

My invention relates to metal windows, and in the embodiment presented I have shown an improved sliding window of the type in which the sash frames lie in a common plane when the window is closed.

In the accompanying drawings Fig. 1 shows a vertical section of a window embodying my invention with the sashes in closed position; Fig. 2 is a section on line 2-2 of Fig. 1; Fig. 3 is a section similar to Fig. 2 but showing the sashes in open position; Fig. 4 is a sectional view taken in the same direction as Fig. 1, but showing the sashes in open position. In this view the solid lines show the parts which are located within the jambs and dot and dash lines are used to indicate parts which would lie in front of the planes on which the sections are taken. Fig. 5 is a sectional view, looking at one jamb from the rear (inside) face of the window.

Referring to these drawings, the upper sash, which is designated by the letter A, has two main side plates 10 which are adapted to enter the jamb and are bent to engage the edge and one face of the sheet of glass as shown in Figs. 3 and 4. Attached to the side plates 10 are glass stops 11. At the top of sash A the main frame comprises a plate 12 which is bent to engage the edge and one face of the sheet of glass in the same way as plate 10. Plate 12 is adapted to enter the lintel and is connected to plates 10 by mitred joints. Glass stop 13, corresponding to glass stop 11, is attached to plate 12. The bottom portion of sash A consists of a U-shaped member 14, one leg and the bottom of which are brazed with mitred joints to plates 10; the other leg, which lies in the same plane as plate 13, serves to hold the glass in place. At various points along the length of member 14, strips 15 are struck down from the leg which lies in the same plane as the bottom end of plate 12. Member 16, the shape of which is clearly shown in Fig. 1, is adjustably attached to strips 15 and serves as part of the meeting rail of sash A.

The lower sash which is designated by the letter B has a meeting rail made up of parts identical with those of sash A, but located in inverted position. U-shaped mem-

ber 17 corresponds to the U-shaped member 14 and has struck out from it strips 18, to which member 19 is adjustably connected. 55 Sash B has two main side plates 20 which are bent to engage the edge and one face of the glass and are then bent forward and out so that the portion which enters the jamb lies in the same plane as the portion 60 which engages one face of the sheet of glass. This is clearly shown in Fig. 3. It is to be noted from Figs. 3 and 5 that the sash plates 20 of sash B do not extend into the jamb as far as the sash plates 10 of sash A. However, near its top, each sash plate 20 has a wing portion 21 which extends into the jamb 65 the same distance as plate 10 of sash A and at the bottom each plate 20 has another wing portion 22 which likewise extends into the jamb the same distance as plate 10 of sash A. These wings 21 and 22 are adapted to cooperate with the guide cams of the lower sash in a manner which will be explained 70 hereafter.

The bottom rail of sash B comprises a plate 23 of approximately the same cross section as plates 20, to which it is attached by brazed mitred joints as shown in Fig. 5. Sash B is provided with glass stops 24 which 80 are attached to plates 20 and a bottom glass stop 25 which is attached to plate 23. Glass stop 25 also extends down sufficiently far to contact with the sill. An additional U-shaped strip 26 is attached to the bottom 85 rail and serves to stiffen the bottom rail, contact with the sill, and to supply a handle for opening and closing the lower sash. The arrangement of parts 23, 25 and 26 is shown in Fig. 1.

The lintel comprises a hollow boxlike portion 27 which is slotted to receive plate 12. Adjustably connected to lintel 27 is a U-shaped member 28 into which plate 12 is adapted to extend. By moving U-shaped 90 member 28 the same result can be obtained as if the slot in portion 27 could be moved.

Each jamb has a tubular member 29 which forms a portion of the front face of the jamb, all of the outer face and all of 95 the rear face. The balance of the outer face is formed by the member 30 which in cross section is in the shape of the letter J. The shorter leg of member 30 forms a portion of

- the inner face of the jamb and the longer leg of this member extends into the interior of the jamb as shown in Figs. 2 and 3. Member 31, shaped as shown in Figs. 2 and 3, is adjustably connected to the longer leg of member 30 and is bent to form a hook 32. Plate 33 is adapted to enter hook 32 and at its outer edge to interlock with member 29 as shown in Figs. 2 and 3. It is to be noted that plate 33 can be removed if it is slid to the rear, that is, towards the interior of the building and that the removal of plate 33 will not change the position of member 31 or member 30.
- 15 Adjustably connected to member 30 is top guide 34 which has a cross sectional shape as shown in Fig. 2. It is to be noted that guide 34 extends in from the longer leg of member 30 sufficiently far so that its inner edge lies in the same plane as the inner face of the short leg of member 30; in other words, its inner edge lies in the plane of the inner face of the jamb. Top guides 34 extend down from the lintel to the middle of 20 the window so that when the upper sash is closed the bottom of guide 34 lies in about the same horizontal plane as the bottom of U-shaped member 14. At its bottom, guide 34 is beveled upwardly and toward the rear 25 of the window, providing a cam surface 35. Sufficient clearance is provided between guide portion 34 and the shorter leg of member 30 to allow plate 10 to enter with a sliding contact and there is sufficient clearance 30 between guide 34 and hook portion 32 of member 31 to allow plate 20 to enter with sliding clearance. When the window is closed plates 20 of lower sash B will lie against the short leg of member 30 and 35 plates 10 of upper sash A will lie immediately above them and will be held against members 30 by guides 34. As the lower sash is raised, the curved corners of members 17 and 14 will act as cam surfaces to 40 force the lower sash out of the upper sash; at about the same time, wing 21 will strike against cam surface 35 of guide 34 so that as the lower sash continues its upward movement, it will slide between guides 34 and 45 hook shaped portions 32 of members 31.
- 50 In order to cause the lower sash B to move into the plane of the upper sash A, as the window is closed, I supply lower guides 36. These are of a shape similar to upper guides 34 and are likewise adjustably mounted on the longer leg of member 30. However, guides 36 extend in toward the face of the jamb only about half as far as guides 34 so that the main portion of plate 20 cannot contact with guides 36, although the wings 21 and 22 will contact with guides 36. Guides 36 extend upwardly from a short distance above the jamb to a point a short distance below guides 34. At its lower edge the inner portion of each guide 36 is bent forward 55 to form a stop 37 to limit the downward movement of upper sash A and is beveled upwardly and to the rear to form cam surface 38. At its upper edge the inner portion of guide 36 is bent rearwardly to form 70 the projection 39 and is beveled upwardly and to the rear to form cam surface 40. Plates 41 are adjustably connected to the longer legs of members 30 at the bottom and are provided with cam faces 42. The vertical distance between the cam faces 38 and 42 is slightly greater than the height of wings 22, and the vertical distance between cam faces 35 and 40 is slightly greater than the height of wings 21.
- When the lower sash is raised and one pushes it down to close the window, wings 21 will strike projections 39 and wings 22 will strike plates 41 and these wings by riding on cam surfaces 40 and 42 respectively 85 will cause lower sash B to move forward into the plane of the upper sash A. When these sashes are in the same plane, the lower portion of member 16 will contact with the inverted U-shaped member 17 and the upper portion of member 19 will contact with U-shaped member 14. Additional downward movement of sash B will cause wings 21 to move down to the outside of guide 36 and will cause wings 22 to move 90 down on the outside of vertical portion 43 of the sill, and thus lower sash B will be held firmly in place and cannot be moved except in an upward direction; and because the contacts between the two meeting rails 95 lie in vertical planes, the additional downward movement of sash B after it has entered the plane of sash A, will not open any joint between the meeting rails. It is thus apparent that by so forming the meeting 100 rails that relative vertical movement of the two sashes while in one plane can be had without opening the joints between the meeting rails, I am able to build a window the sashes of which are adapted to lie in a 105 common plane when the window is closed and have this window so constructed that simple up-and-down movements of the sashes will cause the sashes to take their desired position without the operator thinking 110 of horizontal movement; at the same time, when the window is closed the sashes will be held firmly in place and all this is accomplished without providing any moving parts other than the sashes themselves. 115
- The window is first assembled with members 31 and plates 33 removed. Upper sash A is then put in place and guides 34 set so as to allow sliding clearance of this sash. Lower sash B is then put in place in its 120 closed position and guides 36 are set to allow sliding clearance. Plates 41 are adjusted in relation to the vertical portion 43 of the sill. The lower sash is then raised and member 31 is set to allow a sliding clearance 125 130

of the lower sash between it and guides 34. These adjustments can all be made in the factory. Weight chains which are indicated at 44 and 45 are then attached to plates 10 and 20 respectively, in the usual manner and passed over the usual pulleys which are connected with the lintel, and the weight chains are attached to the weights C and D. If a weight spreader is used as indicated at 46, it may be removably connected with the sill and lintel in any desired manner. It will be noted that the weights C and D can be inserted by removing plate 33 and that the removal of plate 33 will not in any way affect the adjustment of the sash clearances. This is of great importance, for the sash frames are shipped with the weights removed, and if the insertion of the weights after the window is built into place demands the removal of members which affect the sash adjustments, then it is necessary to have an expert go over each window after the sashes are in place, so that these adjustments will be properly made. By the construction here provided, all sash adjustments can be made at the factory and do not need to be changed thereafter. As a matter of fact, the window weights can be removed even after the window has been built into place without even opening the window.

It may also be noted, as shown in Fig. 2, that lower sash plate 20 is of such shape that when the window is closed this plate will cover the lower portion of the gaps between members 31 and 30. The upper portion of these gaps will be largely filled by guides 34.

What I claim is:

1. A window-frame and sash construction comprising jambs, sashes adapted to slide in said jambs with their frames in different planes and to move into such a position when the window is closed that their frames will lie in a common plane, cooperating members forming fixed portions of the lower sash and the jambs respectively, adapted as the lower sash is moved down, automatically to cause the meeting rail of the lower sash to be moved into the plane of the upper sash and adapted when the lower sash is in closed position to hold the upper part of the lower sash against substantial movement resulting from horizontal pressure exerted on the front (outside) face of the lower sash, automatic means for causing the lower part of the lower sash to be moved into the plane of the upper sash as the window is closed, and meeting rails on the sashes of such shape as to form a joint between the sashes when the window is closed, and of such shape as to permit the initial opening movement of the lower sash to be substantially vertical.

2. A window-frame and sash construction comprising jambs, two sashes adapted to slide in the jambs, the sashes being of such

a height that when the window is closed, they can lie in a common plane with substantial vertical clearance between them so that the lower sash can be raised a limited distance while in the plane of the upper sash, and members extending respectively upwardly from the lower sash and downwardly from the upper sash, adapted when the window is closed to close the joint between the sashes without preventing relative movement of the sashes while in the same plane.

3. A window-frame and sash construction as defined in claim 1 and further characterized by having contact portions on the lower sash and stops attached to the jambs in such positions that when the lower sash is closed, the stops will cooperate with such contact portions to hold the lower sash in the plane of the upper sash, but after the lower sash has been raised in the plane of the upper sash the lower sash will be free to move out of the plane of the upper sash.

4. A window-frame and sash construction comprising jambs, sashes adapted to receive panes of glass and having plates adapted to extend into the jambs, such plates being of a thickness less than the maximum thickness of the side members of the sashes, the plates of the lower sash being adjacent to the front (outside) face of the glass and the plates of the upper sash being adjacent to the rear (inside) face of the glass, openings in the jambs adapted to receive the plates, movable members forming part of the jambs, adapted to hold the plates of both sashes in a common plane when the window is closed and adapted to move as the window is opened to permit one of the sashes to move into a different plane, and means for limiting the movement of such members so that the back and forward movement of such members is less than the maximum thickness of the side members of the sashes.

5. A window-frame and sash construction, comprising jambs, sashes adapted to slide in the jambs, means for adjusting the clearance between the sashes and the jambs, a weight compartment in each of the jambs and a removable plate admitting to each such weight compartment and forming a portion of the inner face of each jamb, such plates being removable without changing the adjustment of the clearances between the sashes and the jambs, and so positioned that they do not contact with the sashes when the window is closed and may be removed after the window has been built into a finished wall.

6. A window-frame and sash construction comprising jambs, front and rear plates each forming a portion of the inner face of one of said jambs, and positioned with a space between the respective front and rear plates, sashes adapted to slide in such spaces, means

for holding the upper sash in sliding contact with said front plates, automatic means for causing the lower sash when pushed up to take a position between the upper sash and the rear plates, and when pushed down, to make a joint with said front plate for substantially the height of the lower sash, and rearwardly extending portions forming part of the lower sash, adapted, when the window is shut, substantially to close the lower part of the space between said front and rear plates.

HARRY E. CAMPBELL.
